CLAIM

The ornamental design for a receiver component for vehicle remote control, as shown and described.

DESCRIPTION

FIG. 1 is a perspective view of a receiver component for vehicle remote control showing my new design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; and, FIG. 9 is a perspective view of the receiver component for vehicle remote control where the receiver component for vehicle remote control is in a configuration of use. The broken lines in FIG. 9 showing a cover depict environment and form no part of the claimed design. The other broken lines in the drawings depict portions of receiver component for vehicle remote control and form no part of the claimed design.
